UNITED STATES PATENT OFFICE

HARRY RALPH RICARDO, OF LONDON, AND JOHN FORSTER ALCOCK, OF WORTHING, ENGLAND; SAID ALCOCK ASSIGNOR TO SAID RICARDO

FLUID-PRESSURE ENGINE, PUMP, AND COMPRESSOR

Application filed April 11, 1927, Serial No. 182,884, and in Great Britain April 22, 1926.

This invention relates to fluid pressure engines, pumps and compressors of the sleeve valve type in which the sleeves have motion imparted thereto from a plurality of rotating

nism driven from the crank shaft, such that the motion of this member causes rotation of each and all of the sleeve operating members.

Preferably the parts are so proportioned as to impart to the sleeve operating members a substantially uniform rate of rotation but, if desired, they may be given a non-uniform rate of rotation for example by arranging

55

that the axes of the circles followed by the ends of the arms on the oscillating and reciprocating member do not coincide with the axes of rotation of the sleeve operating members or, alternatively, by employing operating arms for the sleeve operating members of

60

different lengths from the arm through which motion is imparted to the oscillating and reciprocating member.

65

In engines having only a single row of cylinders all the sleeve operating members will normally be arranged in a row with their axes parallel to one another, but in engines of the V or other types having two or more rows of cylinders a separate row of sleeve operating members will normally be provided for each cylinder row and in this case either a separate oscillating and reciprocating member may be provided to operate each

70

row of sleeve operating members or one oscillating and reciprocating member may operate the sleeve operating members for two rows of cylinders.

75

Inertia forces due to the motion of the oscillating and reciprocating member may be balanced by counter-weights on the various rotating members or on shafts specially provided for the purpose, or other known means may be employed.

85

The invention may be carried out in various ways, but two alternative constructions according to this invention are illustrated diagrammatically by way of example in the accompanying drawings, in which

90

Figure 1 is a diagrammatic perspective view of one form of sleeve valve operating mechanism according to this invention,

95

Figure 2 is a similar view to Figure 1 of an alternative form of sleeve valve operating mechanism according to this invention,

100

Figure 3 is a section on the axis of one of

5 sleeve operating members, and has for its object to provide improved actuating mechanism for such sleeve operating members which will be inexpensive to produce and silent in operation.

10 The invention may be applied to fluid pressure engines, pumps or compressors in which each sleeve has a plain reciprocating motion imparted thereto for example by means of a connecting rod engaging a crank pin or its

15 equivalent on one of the rotating sleeve operating shafts or like members. The invention is particularly applicable, however, to engines of the kind in which each sleeve has a combined oscillating and reciprocating motion

20 imparted thereto since experience has shown that the most convenient way of operating the sleeves in such engines is to drive each sleeve from a rotating member through a spherical joint or other flexible coupling

25 eccentrically mounted on such member.

In multicylinder engines of the above general type it is generally necessary to provide a separate sleeve operating member for the sleeve or sleeves controlling the ports in each 30 cylinder and a difficulty arises in providing a drive for these members which shall at once be silent in operation and inexpensive to produce. In known constructions some form of gearing has generally been employed for this

35 purpose but gearing, to be satisfactory, requires a high degree of accuracy in construction both as regards the gears themselves and as regards the relative positions of the various shafts carrying the gears, and a gear

40 drive is, therefore, expensive. The present invention eliminates to a large extent such gearing and provides an arrangement which does not require such accurate construction as was necessary where gearing was employed.

45 According to the present invention an interconnection is provided between each of the rotary sleeve operating members and a member to which a combined oscillating and reciprocating motion is imparted by mecha-

the rotary sleeve-operating members showing a constructional form which may be employed in either of the arrangements shown in Figures 1 and 2, and

5 Figure 4 is a section on the line 4—4 of Figure 3.

In the construction illustrated in Figure 1 the operating gear is for an engine of the four-cylinder type in which the inlet and exhaust ports in each cylinder wall are controlled by a single sleeve valve A having a combined oscillating and reciprocating motion imparted thereto. The desired motion is imparted to each sleeve by a short rotary sleeve operating member B mounted in bearings B¹ with its axis at right angles to the axis of the sleeve and to a point eccentric to the axis of rotation of which the sleeve is connected by means of a crank pin or the like 10 B² engaging a spherical joint or other flexible coupling in the sleeve in known manner. Alternatively a pin carried by the sleeve may engage with a spherical joint or the like eccentrically mounted in the member B.

15 The end of each of the rotary sleeve operating members B remote from the sleeve carries at a point eccentric to its axis of rotation a spherical joint or other flexible coupling D which is engaged by the free end 20 E¹ of an arm E carried on an intermediate shaft F mounted to slide and oscillate in bearings F¹ carried by the engine casing. The shaft F is disposed at right angles to the axis of rotation of the sleeve operating shafts B and is adapted to have motion imparted thereto by mechanism driven from the crank shaft G of the engine, a combined oscillating and reciprocating motion such that the outer ends E¹ of the arms E thereon 25 will move in substantially circular paths and thus will cause rotation of the rotary sleeve valve operating members B. The spherical joint D through which the motion is transmitted from the end E¹ of each arm E to its rotary sleeve operating member B is conveniently mounted in a radial slot H which permits it to move radially or axially but not circumferentially relatively to its rotary sleeve operating member B so as to allow 30 for the swinging movement of the arms E and for any slight inaccuracies which may exist in the relative positions of the various parts or in the motion imparted to the oscillating and reciprocating shaft F. In this way it will be seen that jamming of the parts due to small inaccuracies in alignment are 35 prevented since such errors can be taken up either by radial movement of the spherical joints D or by rotational movement of the sleeve operating members B, only slight irregularity in the rotation of the members B resulting in either case.

40 The desired oscillating and reciprocating motion may be imparted to the shaft F in various ways. In the construction shown in

Figure 1 a short driving member J similar to and disposed parallel to the rotary sleeve operating members B is connected to the free end K¹ of a radial arm K on the intermediate shaft by means of a spherical joint or 45 other flexible coupling as shown. In some cases this spherical joint may be mounted in a radial slot in the driving member J but in such a construction the spherical joint connecting one of the arms E to its rotary member B must be held from radial movement relatively to its rotary member so as to ensure the correct motion of the member F. The rotary driving member J is operatively connected through suitable gearing L, L¹, L² 50 to the crank shaft G, this gearing conveniently including a worm or skew gear L³ or other form of right angle drive and being such that the shaft J will be rotated at half crank shaft speed.

55 In the alternative construction illustrated in Figure 2 the arrangement of the rotary sleeve operating members B and their connections with the sleeves A and the arms E of the oscillating and reciprocating member F is similar to that employed in the arrangement shown in Figure 1. In the construction shown in Figure 2, however, the desired oscillating and reciprocating motion is imparted to the shaft F through a second oscillating and reciprocating member M having its axis at right angles to that of the member F. The member M is adapted to slide and also to oscillate in vertical bearings M¹ and has two arms M², M³, one of which M² is 60 connected through a spherical joint or the like to the free end of the driving arm K on the shaft F while the other M³ engages a spherical joint or the like N¹ mounted in a gear wheel N driven through gearing N² 65 N³ from the crank shaft G. In this way a substantially circular motion is imparted to the outer end of the arm M² whereby the desired combined oscillating and reciprocating motion is imparted to the member F.

70 Figures 3 and 4 show a constructional form which may be employed in either of the arrangements diagrammatically illustrated in Figures 1 and 2.

75 In the construction illustrated in Figures 3 and 4 the oscillating and reciprocating member F is constructed as a hollow tube so as to have relatively great torsional stiffness while the radial arms E and K thereon are formed separately from this tube and are connected thereto by passing their inner ends E² through the tube and maintaining them in position by means of nuts E³. The outer end E¹ of each arm is conveniently formed spherical as shown and constitutes the inner member of the spherical joint D, the outer member of this joint surrounding the spherical end of the arm and being provided with oppositely disposed flat outer surfaces adapted to engage with the sides of the slot H in 80

the rotary sleeve operating member B so as to be slidable therein.

The outer member of the spherical joint D is further conveniently formed in two halves held together between the sides of the slot in which it is disposed.

The rotary sleeve-operating members B are each conveniently in the form of a short drum as shown carried in bearings B¹ which completely surround it and are mounted in the engine casing F². Each drum B carries a crank pin or the like B² which engages a spherical or other self-aligning joint B³ in the sleeve A whereby motion is transmitted from the rotary members B to the sleeves.

It is obvious that the rotary motion imparted to one or more of the drums B may be utilized to drive some element other than a sleeve valve. For instance, a magneto or other auxiliary device associated with the engine may be driven in this manner.

It will be seen that with sleeve operating mechanism according to this invention the amount of gearing required is small as compared with arrangements previously generally employed so that a reduction in the cost of production is effected while the sleeve operating mechanism will be practically silent in operation.

It is to be understood that the details of construction and the manner in which the desired motion is imparted to the oscillating and reciprocating member may be varied within wide limits without departing from this invention.

What we claim as our invention and desire to secure by Letters Patent is:—

1. In a mechanical movement, the combination with a rotary driven element, of a member mounted for rectilinear reciprocation transversely of the axis of said element and for rotation, an arm on said member, means operatively connected to said member for causing the outer portion of said arm to follow a definite substantially circular path, and means mounted on said element for movement radially thereof having a pivotal connection with said arm.

2. In a mechanical movement, the combination with a rotary element, of means mounted to rotate about an axis parallel with the axis of rotation of said element, a member mounted for rotation and for rectilinear reciprocation transversely of the axis of said element, a pivotal connection between said means and said member, and a pivotal connection freely slidable radially of said element between said element and said member.

3. In a mechanical movement, the combination with a rotary element, of means mounted to rotate on an axis parallel with the axis of said element, a member mounted for rotation and for rectilinear reciprocation transversely of the axis of said element, a pivotal connection between said means and

said member, and a pivotal connection between said member and said element freely movable radially of said element.

4. Mechanism for transmitting motion comprising a member having a combined alternating rotary and rectilinear reciprocating motion, a plurality of rotatable members disposed with their axes substantially at right angles to the axis of rotation of the alternate rotating and reciprocating member, a series of arms on the alternate rotating and reciprocating member, a driving member having circular motion about an axis substantially at right angles to that of the alternate rotating and reciprocating member and connected to the free end of one of the arms thereon so as to impart the desired alternate rotation and reciprocating motion to such member, and a connection between the free end of each of the remaining arms and one of the rotary members whereby the movement of the alternate rotating and reciprocating member will cause rotation of each and all of these rotary members, the connection between the free end of an arm and its associated part being such in the case of every arm but one that there is permitted to the free end of the arm a radial movement relatively to the axis about which moves the member to which it is connected.

5. Mechanism for transmitting motion comprising a member having a combined alternating rotary and rectilinear reciprocating motion, a plurality of rotatable members disposed with their axes substantially at right angles to the axis of rotation of the alternate rotating and reciprocating member, a series of arms on the alternate rotating and reciprocating member, a driving member having circular motion about an axis substantially at right angles to that of the alternate rotating and reciprocating member, a connection between the free end of one of the arms and the driving member whereby the desired motion will be imparted to the alternate rotating and reciprocating member, and a connection between the free end of each of the remaining arms and one of the rotary members whereby the movement of the alternate rotating and reciprocating member will cause rotation of each and all of the rotary members, such connections being so constructed and arranged that there is permitted to the free end of each arm a radial movement relatively to the axis of rotation of the rotary member to which it is connected.

6. Mechanism for transmitting motion comprising a member having a combined alternating rotary and rectilinear reciprocating motion, a plurality of rotatable members disposed with their axes substantially at right angles to the axis of rotation of the alternate rotating and reciprocating member, a driving member having circular motion about an axis substantially at right angles to that of the alternate rotating and reciprocating member.

angles to that of the alternating rotating and reciprocating member, a series of arms on the alternating rotating and reciprocating member, a ball member on the free end of each arm, one of such ball members engaging a socket in the driving member whereby the desired motion is imparted to the alternate rotating and reciprocating member, a socket member mounted so as to be capable of sliding in a radial slot in each rotary member, each of these socket members being engaged by the ball member on the free end of one of the remaining arms as set forth.

In testimony whereof we have signed our names to this specification.

HARRY RALPH RICARDO.
JOHN FORSTER ALCOCK.
